DESIGN FOR A PUNCH BOWL OR SIMILAR ARTICLE

Robert A. Kelly, East Pittsburgh, Pa., assignor to
United States Glass Company, Pittsburgh, Pa.,
a corporation of Pennsylvania

Application February 23, 1938, Serial No. 75,334

Term of patent 3½ years

To all whom it may concern:

Be it known that I, Robert A. Kelly, a citizen of the United States, residing at East Pittsburgh, county of Allegheny, in the State of Pennsylvania, have invented a new, original, and ornamental Design for a Punch Bowl or Similar Article, of which the following is a specification, reference being had to the accompanying drawing, forming a part thereof, in which—

Figure 1 is a top plan view showing a half of a punch bowl or similar article of my new design taken through its center, it being understood that the other half is exactly the same as the half shown;

Figure 2 is a bottom plan view showing the

half of the punch bowl of Figure 1 taken along its center line, it being understood that the other half is exactly the same as the half shown; and

Figure 3 is an elevational view of the punch bowl of Figures 1 and 2, the lefthand portion thereof being a section taken along the line III—III of Figure 1, and the righthand portion being a side view, it being understood that the section or broken portions of the punch bowl are the same as the portions illustrated.

I claim:

The ornamental design for a punch bowl or similar article, substantially as shown and described.

ROBERT A. KELLY.
